UNITED STATES PATENT OFFICE.

JOHN H. ELSPASS, OF DENVER, COLORADO, ASSIGNOR TO THE ELSPASS ROLLER QUARTZ MILL AND MANUFACTURING COMPANY, OF PUEBLO, COLORADO.

PULVERIZING-MILL.

No. 800,089.

Specification of Letters Patent.

Patented Sept. 19, 1905.

Application filed June 22, 1904. Serial No. 213,740.

To all whom it may concern:

Be it known that I, JOHN H. ELSPASS, a citizen of the United States, residing in the city and county of Denver, and State of Colorado, have invented certain new and useful Improvements in Pulverizing-Mills; and I do declare the following to be a full, clear, and exact description of the invention, such as will enable others skilled in the art to which it applies to make and use the same, reference being had to the accompanying drawings, and to the letters of reference marked thereon, which form a part of this specification.

My invention relates to improvements in pulverizing-mills of the class in which an annular rotary mortar is mounted on rollers and actuated by means of suitable gearing, pulverizing-rollers being mounted above the mortar and coöperating therewith to perform the pulverizing function, the mortar being provided with a surrounding screen of a mesh according to the fineness to which it is desired to reduce the material under treatment. Hence this invention belongs to the same class as my previous patent, No. 651,798, dated June 12, 1900, and also the same class as the inventions covered by my simultaneously-pending applications, serially numbered 141,075 and 205,211, respectively, and filed January 29, 30, 1903, and April 27, 1904, respectively.

My present invention relates to certain novel features of construction, relating both to the apparatus as a whole and to details of its construction, which may be considered improvements on the construction set forth in the previous patent and applications, all of which will now be described in detail, reference being made to the accompanying drawings, in which is illustrated an embodiment thereof.

In the drawings, Figure 1 is a central vertical section taken through my improved pulverizing-mill. This section may be said to be taken on the line 1 1, Fig. 2, parts, however, being left in elevation. Fig. 2 is a top or plan view of the apparatus shown on a reduced scale. Fig. 3 is a fragmentary sectional view taken on the line of the operating-shaft, parts being shown in elevation. Fig. 4 is a partial horizontal section taken on the level of the 45 grinding-floor or pulverizing-face of the mortar (see Fig. 1) looking downwardly, parts being broken away. Fig. 5 is a perspective view of the plow forming a part of the mechanism. Fig. 6 is a similar view of a scraper

also forming a part of the mechanism. Fig. 55 7 is a top view of the plow and the supporting part of the framework. Fig. 8 is a front view of the plow with the supporting frame-piece shown in section, the mortar being indicated by dotted lines. Fig. 9 is a top view 60 of a washer used in fastening the plow to its frame-supporting part. Fig. 10 is a horizontal section taken through one of the outer posts looking downwardly on the plow-supporting frame-bars. 65

The same reference characters indicate the same parts in all the views.

Let A designate the bed-plate of the apparatus, upon which are mounted a number or a series of inner posts B and a number of outer posts C. Between these two series of posts is located an annular rotary mortar D, having a gear E fast on its lower surface and with which meshes a driving-gear F, fast on an operating-shaft G, journaled in suitable boxes 70 G'. Upon this shaft are mounted fast and loose pulleys H. The mortar is supported by frusto-conical rollers I, fast on shafts I', journaled in boxes I'. The shafts I' are slightly inclined from their outer extremities downwardly, and the inner end of the inner journal-box is closed, as shown at I³, to prevent the escape of the lubricating material which is introduced at the outer extremity of the shaft. The bottom of the mortar which 85 engages the supporting-rollers I is beveled to correspond with the beveled faces of the frusto-conical rollers, whereby there is a perfect rolling contact between the mortar and the supporting-gears during the operation 90 of the machine. The upper surface of the mortar is provided with a hardened-steel ring D', whose upper surface forms the pulverizing-face of the mortar. Outside of this ring the mortar is provided with a vertical offset 95 D², between which and the ring is placed a wood filling D³. Above this offset the mortar is provided with an annular ledge D⁴, surrounding the pulverizing-face of the mortar, the face of the ledge being downwardly inclined from its inner circumference to its outer circumference. At the outer circumference of this ledge there is a slight upward projection D⁵, above which is located the surrounding screen D⁶, through which the pulverized 100 material escapes from the mortar into the surrounding trough D⁷, whose bottom slopes downwardly from a point D⁸ to a discharge- 105

chute D⁹, where the pulverized material in the form of pulp escapes. This trough D⁷ consists of an outer wall D¹⁰, whose upper edge is nearly as high as the top of the mesh portion of the screen, while its lower edge extends below the screen. The inner wall D¹¹ extends downwardly from the lower surface of the ledge to the bottom D¹² of the trough. This trough is therefore constructed to prevent any of the material which passes thereto from the mortar from escaping except by the regular outlet or discharge-chute D⁹. The mortar is also provided with an inner wall D¹³, which rises from the bottom of the mortar vertically to the height of the ring D' and is thence inclined inwardly, increasing the width of the mortar on the inside, thereby making room for the lower extremities of the conduits J, leading from the centrally-located hopper K, mounted on the upper part of the framework within the space surrounded by the inner series of posts B. The hopper K is provided with flanges K', which rest upon the top of the frame.

The posts C are inwardly inclined from their lower extremities upwardly, as shown at C', to a point C², from which point they extend upwardly vertically, as shown at C³. The inner posts B also have lower inclined portions B' parallel or approximately parallel with the portions C' of the outer posts. From a point B² the inner posts extend vertically upwardly, as shown at B³. By virtue of the inclined portion C' of the outer series of posts the mill is securely braced and room is made between the mortar and the posts for the trough D⁷, while the inclined portions B' of the inner posts also have a tendency to brace the structure and give it great stability. The vertical positions of the upper portions of these posts are also preferred as a support for the roller axles. The upper vertical portions of both series of posts are bifurcated to receive boxes L and L', in which the extremities of the roller-axes L² are journaled. Above these axes and bearing on the boxes are the coil-springs L³, whose upper extremities are engaged by cross-heads or bearing-plates L⁴, which are engaged by tension-screws L⁵, threaded in the top of the frame, whereby the tension of the springs may be regulated at will. Upon these shafts L² are mounted and made fast the pulverizing-rolls M, each consisting of a body part M', a detachable part M², and a hardened-steel tire M³. The part M where it engages the axle is provided with an inwardly-projecting collar M⁴, which is surrounded by the part M², the latter being secured to the body part M' by screws M⁵. The parts M' and M² at their peripheries are inclined downwardly from their flat or vertical faces, making the outer periphery of the roller lowest at its center. The adjacent face of the tire M³ is beveled to fit the outer periphery of the roller, so that when the bolts M⁵ are applied to hold the

part M² in place the tire is locked in position. To remove the tire, it is only necessary to remove the screws M⁵, after which the tire may be easily removed by striking it on the outside, whereby it, together with the part M² of the roll, is driven inwardly. This is an important feature, since it is necessary to change these tires quite frequently, owing to the great wear to which they are subjected during the operation of the mill. The shaft L² is provided with an outer collar L⁶, which bears against an inner flange formed on the journal-box L. The axle is also provided with an offset L⁷, against which the body of the roller bears, whereby the latter is prevented from moving outwardly on the shaft. The inner extremity of the shaft is also provided with an offset L⁸, which bears against the inner box L'. The shaft is thus locked against shifting in either direction, while the roll, which is connected with the shaft to rotate therewith, is prevented from sliding outwardly thereon. When the machine is in operation, the rolls bear upon the upper surface of the ring D', and the pressure is regulated by the tension of the springs L³.

The inner posts B, as shown in the drawings, are cast integral with a ring N, which engages a ring O, connected with the mortar, whereby the latter is accurately centered during the operation of the mill. The outer portion of the ring O is secured to the mortar by bolts O², while bolts O³ are used to secure the ring O to the brackets O'. To the top of the ring N outside of the posts is secured a plate Q, which overlaps the ring O and forms a guard to prevent dust or foreign particles of matter from passing between the engaging or adjacent inclined faces of the two rings.

Mounted upon the bars R, which are secured to the outer series of posts above the top of the mortar, is a number of plows S, each of which is provided with a body part S' and two projections S² and S³. The part S' projects horizontally above the ledge D⁴, whereby the coarse material not pulverized to the desired fineness is carried outwardly to the pulverizing-face of the mortar, while the projection S³ extends inwardly over the pulverizing-face of the mortar and has a tendency to carry any material in its path inwardly toward the center of the pulverizing-face or in position for the rolls to act most effectively thereon. Above the arm S² the body S' of the device is provided with a curved face S⁴, which also occupies a position above the ledge D⁴ and forces the pulp outwardly against the screen as the mortar rotates, whereby the pulverized material is made to pass through the screen and into the surrounding trough D⁷. This plow occupies a diagonal position with reference to the ledge and the pulverizing-face of the mortar, as shown in Figs. 2 and 7 of the drawings. Into the body of each plow is threaded a shank

⁵ ¹⁰ ¹⁵ ²⁰ ²⁵ ³⁰ ³⁵ ⁴⁰ ⁴⁵ ⁵⁰ ⁵⁵ ⁶⁰ ⁶⁵ ⁷⁰ ⁷⁵ ⁸⁰ ⁸⁵ ⁹⁰ ⁹⁵ ¹⁰⁰ ¹⁰⁵ ¹¹⁰ ¹¹⁵ ¹²⁰ ¹²⁵ ¹³⁰

S^b , which passes upwardly through a slot formed in a lug R' integral with the bar R . This lug is grooved at the top, as shown at R^6 , to receive a washer R^2 , having parallel sides which engage the groove of the lug and lock the washer from turning. The shank of the plow is flattened on two opposite sides, and the opening R^3 of the washer is shaped to fit this shank, whereby the plow is prevented from turning when its stem or shank engages the opening in the washer. The lug R' is also grooved on its lower side, as shown at R^7 , to receive a nut R^4 , which also fits into the groove to prevent the nut from turning. The washer R^4 and the nut R^2 are applied to the shank of the plow before the latter is inserted in a slot of the lug R' . The shank is then inserted, in which event the nut and washer are locked against rotation on the lug. The shank is also locked against rotation by virtue of its flattened sides, which fit into the openings of the washer. A nut R^5 is then screwed down upon the shank to engagement with the washer. In this manner each plow is supported in operative relation with reference to the mortar.

As shown in the drawings, there are four pulverizing-rolls, the individual rolls of each pair being located on opposite sides of the center of the mill. One of the plows S is located between each two rolls and in such a manner as not to interfere with the operation of the latter. From the position of the plows in Fig. 2 of the drawings it will be understood that the mortar is rotated in the direction of the arrows in said view. In this event the operation of the plow as heretofore described will be readily understood—that is to say, the projection S^2 will throw the coarse material from the ledge to the pulverizing-face of the mortar, while the curved face S^4 will throw the pulp or the pulverized material mixed with water outwardly against the screen. At the same time the curved face of the projection S^3 has a tendency to throw the material inwardly toward the center of the pulverizing-face of the mortar in order to bring it into proper position with reference to the rolls.

A number of scrapers T are also mounted on the frame-bars R and in suitable proximity to the screen, whereby as the mortar rotates the scrapers act to keep the screen clear on the inside. These scrapers consist of a body part T^1 , having a curved face T^2 , which occupies a position above the ledge and quite close to the screen. The position of these scrapers is best illustrated in Fig. 2. The face or vertical surface T^3 occupies a position next to the screen, while the point T^4 extends in the direction opposite that in which the mortar is turning, whereby the curved or forwardly-projecting face of the scraper has a tendency to throw the pulp inwardly away from the screen for the purpose stated. Into the body part of the scraper is threaded a shank T^5 , to which is applied a lock-nut T^6 . The upper

part of the shank enters a slot formed in a lug R^6 and is secured by nuts T^7 and T^8 , which engage the lug R^6 both above and below. The arrangement for preventing the scraper from turning may be substantially the same as that explained in connection with the plow S , and therefore need not be further described in detail.

From the foregoing description the use and operation of my improved pulverizing-mill will be readily understood. Assuming that the mill is set up and the springs L^3 placed under proper tension, whereby the normal pressure of the rolls M on the pulverizing-face of the mortar is properly regulated, the driving-pulley H is connected with any suitable power, which is transmitted to the mortar through the instrumentality of the gears, as heretofore described. The material to be treated is then fed into the hopper K and passes downwardly through the inclined conduits J into the inner portion of the mortar, whereby it is brought directly beneath the pulverizing-rolls as the mortar rotates. The coarser material, which works upwardly from the pulverizing-face of the mortar to a position upon the ledge D^4 , is carried backwardly to the pulverizing-face of the mortar by the plow, while the concentrates or heavy metallic values settle upon the upper surface of the ledge D^4 below the plow, which does not extend sufficiently low to scrape off the concentrates. The relative position approximately of the projection S^2 of the plow with reference to the pulverizing-face of the mortar is illustrated in Fig. 8 of the drawings, in which the ledge D^4 is indicated by dotted lines. As the material is pulverized it passes from the pulverizing-face of the mortar over the ledge and is thrown outwardly upon the screen, as heretofore explained. Attention is called to the fact that the material to be treated when fed into the hopper K is in the form of a pulp—that is to say, is mixed with a suitable quantity of water for pulverizing purposes.

The inner and outer series of posts are connected at the top by triangular frame members V ; four of said members being employed, their inner extremities being connected with the inner series of posts by bolts V^1 , while their outer extremities are connected with the outer posts by bolts V^2 . Each of these members has two arms V^3 , which extend outwardly from the center of the mill to an outer arm V^4 .

The posts C are provided with bottom lugs C^4 , which are connected with the base A by means of bolts C^5 . Each post C is provided with two lugs. (See Fig. 2 of the drawings.) The plow-supporting frame-bars R are connected with the outer posts by bolts R^9 , the posts being provided with lugs C^6 . (Shown in Fig. 9 and indicated by dotted lines in Fig. 10.)

The lower extremity of each conduit J is provided with a deflector J' , consisting of a plate which is secured in the lower extremity.

of the conduit and is bent downwardly in front of the open end of the conduit, whereby the material as it leaves the conduit is directed downwardly upon the pulverizing-face of the 5 mortar.

Having thus described my invention, what I claim is—

1. In a pulverizing-mill, the combination of inner and outer series of posts, each series of 10 posts having inclined lower parts whose lower extremities are outermost, the upper portions of both series of posts being vertical and bifurcated, an annular rotary mortar located between the two series of posts, rollers supporting the mortar from below, pulverizing-rolls provided with axles journaled in boxes mounted in the bifurcated vertical portions of the inner and outer posts, tension-springs also located in the bifurcated portions of posts and 15 engaging the boxes from above, and tension-regulating means engaging the springs from above, the pulverizing-rolls coöperating with the mortar to perform the pulverizing function, substantially as described.
2. In a machine of the class described, the combination of inner and outer series of posts, the outer series of posts having inclined lower portions whose lower extremities are outermost, the upper portions of the posts being 20 vertical, axles journaled in boxes engaging the inner and outer series of posts, the posts being open above the axle, coil-springs located in the openings of the posts, tension-regulating means located above the springs, pulverizing-rolls mounted on the axles, and an annular rotary mortar located and suitably supported between the two series of posts, the 25 mortar and pulverizing-rolls coöperating to perform the pulverizing function, substantially as described.
3. In a pulverizing-mill, the combination of inner and outer series of posts, the lower portions of the posts being inclined, their lower extremities being outermost, rolls having 30 axles journaled in the inner and outer series of posts, an annular rotary mortar mounted between the two series of posts and coöperating with the pulverizing-rolls, roller-supports for the mortar, and a trough located between the 35 mortar and the outer series of posts to receive the pulverized material from the mortar, the said trough having an inclined bottom, and an outlet leading from the lowest part of the bottom for the purpose set forth.
4. The combination of inner and outer series 40 of posts, the outer series of posts having inclined lower portions, their upper portions being vertical, an annular rotary mortar located between the two series of posts and suitably 45 supported, a trough surrounding the mortar and located between the latter and the outer series of posts, the outer wall of the trough being outwardly inclined from its upper periphery, the bottom of the trough being downwardly inclined to facilitate the discharge of 50

the pulverized material therefrom, and pulverizing-rolls mounted on axles journaled in the inner and outer series of posts, the said rolls coöperating with the mortar to perform the pulverizing function, substantially as described. 70

5. In a pulverizing-mill, the combination with a suitable frame, of an annular rotary mortar suitably supported between inner and outer series of posts with which the frame is 75 provided, a stationary feed-hopper centrally mounted on the upper part of the frame and occupying the space surrounded by the inner series of posts, the said hopper being provided with conduits leading downwardly and outwardly to the mortar, and pulverizing-rolls provided with axles journaled in the inner and outer posts and coöperating with the mortar to perform the pulverizing function. 80

6. In an apparatus of the class described, 85 the combination with inner and outer series of posts, of an annular rotary mortar located between the two series of posts and provided with a pulverizing-face, and a ledge extending outwardly from said pulverizing-face, 90 pulverizing-rolls supported by the posts and coöperating with the pulverizing-face of the mortar, and plows mounted on the frame and occupying a diagonal position with reference to the pulverizing-face of the mortar and its 95 ledge, each of the said plows having a projection extending outwardly over the ledge and presenting an inclined face to the material on the ledge as the mortar rotates, the inclination of the said face having a tendency 100 to throw the material which comes in contact therewith, inwardly to the pulverizing-face of the mortar, the said plow having a part projecting inwardly over the pulverizing-face of 105 the mortar and having a tendency to throw the material toward the center of said face, the plow being further provided with a curved face located entirely above the first-named projection and curved to throw the pulp outwardly 110 against the screen. 110

7. In a pulverizing-mill, the combination of a suitable frame having an inner series of posts, a rotary mortar surrounding the series of posts, and a stationary feed-hopper located in the central space surrounded by the posts 115 and provided with supporting-flanges resting on top of the frame, the said hopper having conduits leading outwardly and downwardly to the mortar, substantially as described. 115

8. In a pulverizing-mill, the combination 120 with inner and outer series of posts, an annular mortar located between the two series of posts, pulverizing-rolls mounted on the posts and coöperating with the mortar to perform the pulverizing function, a stationary feed-hopper mounted on the frame and located within the central space surrounded by the inner series of posts, and conduits leading outwardly and downwardly to the mortar, 125 their lower extremities having vertical de- 130

pending lips and being arranged to discharge into the mortar for the purpose set forth.

9. In a roller pulverizing-mill, the combination with inner and outer series of posts, 5 an annular rotary mortar located between the two series of posts, a ring mounted on the mortar, another ring mounted on the inner series of posts and co-operating with the mortar-ring to perform the mortar-centering 10 function, and a horizontal plate detachably connected with the ring on the inner series of posts and projecting outwardly over the ring on the mortar.

10. In a roller pulverizing-mill, the combination with a suitable frame, of a circular mortar mounted to rotate, the bottom of the mortar having an annular recess, a wall extending upwardly outside of the recess, a ledge located above and extending beyond the 20 pulverizing-face of the mortar, a screen surrounding the mortar beyond the ledge, a hardened-metal ring located in the recess in the bottom of the mortar, and a wood filling between the ring and the upwardly-projecting wall, the inner circumference of the ledge being higher than the upper surface of the 25 said ring.

11. In a pulverizing-mill, the combination of inner and outer series of posts, an annular

rotary mortar located between the two series 30 of posts, the said mortar having a bottom ring detachably connected with the mortar, an inwardly-inclined wall extending above the upper surface of the ring, an upwardly-projecting wall beyond the outer periphery 35 of the ring, a filling located between the ring and the upwardly-projecting outer wall, a ledge surrounding the ring beyond the last-named wall, the inner periphery of the ledge being above the upper surface of the ring, 40 and a screen surrounding the mortar outside of the ledge.

12. In a pulverizing-mill, the combination with a suitable frame, of an annular rotary mortar and plows mounted on the frame and occupying a position above the face of the mortar, each plow having a body part provided with a curved face on one side, and two projections extending in opposite directions from the body part and located entirely below the 50 curved face of the body part.

In testimony whereof I affix my signature in presence of two witnesses.

JOHN H. ELSPASS.
